Philip Dauphin Lee Kennedy
ATTORNEY

UNITED STATES PATENT OFFICE.

LOUIS G. BEERS, OF TRENTON, NEW JERSEY, ASSIGNOR TO NEW JERSEY WIRE CLOTH COMPANY, OF TRENTON, NEW JERSEY, A CORPORATION OF NEW JERSEY.

WIRE BASKET AND POST THEREFOR.

Application filed May 23, 1922. Serial No. 562,942.

To all whom it may concern:

Be it known that I, Louis G. BEERS, a citizen of the United States, residing at Trenton, county of Mercer, and State of New Jersey, have invented certain new and useful Improvements in Wire Baskets and Posts Therefor, fully described and represented in the following specification and the accompanying drawings, forming a part of the same.

This invention relates to improvements in baskets, and especially to garden baskets used as receptacles for leaves, papers and other such refuse. The invention also includes a novel post forming a part of the basket and adapted for use as a trellis guard, support for plants, fence post and many other uses.

The especial object of the invention is the provision of a simple and cheap garden basket adapted for the burning of refuse without injury to the basket and which may be shipped flat and readily made up into basket form by the gardener or dealer, as required.

For a full understanding of the invention, a detailed description of the invention in its preferred form will now be given in connection with the accompanying drawing forming a part of this specification, and the features forming the invention then specifically pointed out in the claims.

In the drawings—

- Fig. 1 is a side elevation;
- Fig. 2 is a plan view;
- Fig. 3 is a vertical section; and
- Fig. 4 is a detail thereof.

Referring to the drawings, the basket may be formed of wire mesh, expanded metal or the like, but preferably wire netting A having top and bottom selvages, respectively, 1 and 2 is used. The netting A is formed into a cylinder or any other suitable shape with the netting ends overlapped and a plurality of posts 3, preferably of rigid wire are utilized to support the cylinder thus formed and maintain it in basket form. Each post 3 is provided at its upper end with a hook 4, preferably formed integrally therewith by suitably bending the post 3 and near its lower end and preferably on the side opposite to that on which hook 4 is located, with a heavy wire suitably bent to form a leg or prong 5 connected to the post 3 by a side

bar or foot piece 6, which may be secured to the post by welding or brazing but preferably by coiling the end of the side bar 6 tightly thereabout and soldering. The leg 5 and the portion 8 of the post 3 below the foot piece 6 may hereafter be termed prongs. 55

For securing the netting A in cylindrical form, one of the posts 3 is utilized and secured thereto at the point of overlap in the following manner. The prong 8 is passed through the meshes of the two layers of netting A from the inside above the lower selvage 2, and the upper part or selvage 1 of the two layers of netting is then hooked onto the hook 4. With the netting thus held in form, two or more posts 3 are then secured to the single wire netting A at suitably spaced points in a similar manner to form a support for the basket. The side bars 6 thus extend within the basket and form an open bottom on which a pan or other receptacle will be supported, or the basket may be used as a plant support or guard without any bottom other than the side bars. I preferably add a bottom of wire netting cut slightly larger than the cylinder formed by the netting A and forced down against the foot piece 6, as shown in Fig. 3, so that the bottom 7 will be retained within the basket during the emptying. 70

The basket may be made of any size within the length of the wire netting by overlapping the ends more or less and may be held rigid by forcing the prongs 5 and 8 into the earth through foot pressure applied to side bars or foot pieces 6. For the collection of widely distributed refuse, a large basket may be mounted upon a wheeled truck and moved about. Among other uses, the basket is especially adapted as a garbage container and incinerator. 85

The post 3 is especially handy about the garden, not only as a plant support, trellis support and the like but also as a fence post for single wire or wire netting fences. 90

It will be understood that the invention is not to be limited to the particular construction shown, as many modifications may be made within the invention as defined by the claims. 100

What is claimed is:

1. A basket formed by a strip of wire netting or the like and wire posts holding the strip in form and forming a support for

- the basket, a bottom for the basket, and side bars on the posts for supporting the basket bottom.
2. A basket formed by a strip of wire netting or the like, a plurality of posts passed through the lower portion of the netting, hooks on the posts passed through the upper portion of the netting, and side bars on the posts inside the basket.
- 10 3. A basket formed by a strip of wire netting or the like, a plurality of posts passed through the lower portion of the netting, hooks on the posts passed through the upper portion of the netting, side bars on the posts inside the basket and a separate wire netting bottom for the basket.
- 15 4. A basket formed by a strip of wire netting or the like, a plurality of posts passed through the lower portion of the netting, hooks on the posts passed through the upper portion of the netting, and side bars on the posts within the basket forming foot pieces and carrying a prong.
5. A basket formed by a strip of wire netting or the like, having its ends overlapped, a plurality of posts passed through the lower portion of the netting, hooks on the posts passed through the upper portion, one of the posts being thus secured at the point of overlapping, a separate wire netting bottom for the basket, and supports for the basket bottom carried by the posts.
- 20 6. A wire support for making wire baskets and other wire structures having a hook formed at the upper end and on one side thereof, and a side bar and prong at the lower end and on the side opposite that on which the hook is formed.
- 30 7. A wire support for making wire baskets and other wire structures having a hook formed at the upper end, and a separate wire secured to the post by coiling it around the post and forming a side bar and prong.

In testimony whereof, I have hereunto set my hand.

LOUIS G. BEERS.
